UNITED STATES PATENT OFFICE.

GEORGE A. VOLZ, OF CINCINNATI, OHIO.

REVERSIBLE HEEL.

Application filed February 1, 1927. Serial No. 165,199.

My invention relates to improvements in reversible heels for boots and shoes. One of its objects is to enable composition heels, of rubber or molded cork for instance, to be attached to a pair of boots or shoes in such manner as to be readily detachable and reversible, or if desired replaceable with new ones. Another object is to provide improved means of attaching or anchoring the metal attaching members within the composition so as to firmly unite the composition to the metal. Another object is to provide improved metal members adapted to be rigidly attached to the boots or shoes and to which the metal members of the composition heels are detachably and reversibly secured. Another object is to provide improved metal members adapted to be detachably and reversibly attached in pairs by means of which firm and reliable but detachable and reversible attachment of the composition heels to the boots or shoes may be attained. My invention also comprises certain details of form and arrangement, and combination of components, all of which will be fully set forth in the description of the accompanying drawings, in which:

Fig. 1 is a bottom plan view of a composition heel and its attached metal member ready to be attached to a boot or shoe, and embodying in part my invention.

Fig. 2 is a plan view of the metal member shown in Fig. 1, detached.

Fig. 3 is a plan of a portion of a boot or shoe with its attached metal member ready to detachably receive the heel shown in Fig. 1.

Fig. 4 is an enlarged perspective view of the metal member of Fig. 3 detached therefrom.

Fig. 5 is a central vertical section through the shoe shown in Fig. 3 and the heel shown in Fig. 1 slightly separated, but in position to be interengaged and attached together.

The accompanying drawings illustrate the preferred embodiment of my invention, in which 15 represents a composition heel of molded rubber, molded cork composition or similar material. A heel metal member 16 is provided with a substantially central perforation 17, a series of perforations 18 surrounding the perforation 17, a series of extended toes 20, which are off-set at one side of the main portion of the heel member 16 so as to be sunk or anchored deeply into the

body of molded material of the heel 15, while the main portion of the heel member 16 is exposed upon the upper face of said heel member 15 and in a slightly depressed space 22 encircled by an annular raised rim 24. The toes 20 are arranged in a broken circle near the periphery of the heel member 15 so as to secure as ample and firm an anchorage for the metal heel member 16 in the molded member 15 as possible, and so as to enable said metal member 16 to resist all normal strains tending to separate the member 15 from the member 16. For this purpose the toes 20 may also be perforated as at 40 in Fig. 2, if desired.

Metal members 26 have each a series of projections 27 along their edges, and extending to one side of the plane of the member 26, and another series of projections 28 extending to the opposite side of the plane of said member 26. The member 26 is also provided with a centrally located internally screw threaded sleeve 29 extending from the plane of member 26 upon the same side as the projections 27. The metal members 26 are designed to be attached to the leather heel bases 30 of the boots or shoes 31, flush with the lower faces of said heel bases with the projections 27 extending into the heel bases, and the sleeves 29 recessed into said heel bases 30. A series of nails or screws 32 serve to hold the metal members 26 firmly in place relative to the heel bases 30, while the projections 27 tend to resist lateral strain in any direction calculated to detach the metal members 26 from the heel bases 30. The outwardly extending projections 28 register with and are adapted to enter and interengage with the perforations 18 of the metal heel member 16, so as to firmly resist lateral strain tending to separate the plate 26 from the plate 16. A screw 35 introduced through a central recess 36 in the heel member 15 and through the central perforation 17 in the metal heel member 16 and threaded into the sleeve 28 of the metal member 26, serves to firmly but detachably lock each pair of metal members 16 and 26 together against any normal tendency to detach the heel 15 from the heel base 30, and at the same time provides for readily detaching and interchanging the heels 15 upon opposite shoes, to provide for wearing the heels evenly, and for readily renewing the heels if required.

The apparatus herein shown and described is capable of considerable modification with-

in the scope of the claims without departing from the spirit of my invention.

What I claim is:

1. In combination with a pair of shoes
  - 5 having heel bases, a pair of metal base members attached to said heel bases substantially flush with the bottoms of said heel bases, and each provided with projections extending into said heel base, and a series of projections extending away from said heel base, and a threaded sleeve recessed into the heel base, a pair of detachable and interchangeable metal heel members having each a central perforation opposite the threaded sleeve of said metal heel base members, and perforations to register with and engage the outward projections of said metal heel base members, and a series of toe members off-set to one side of the plane of the body of said metal heel members, and a pair of molded composition heel members in the body of which the toe members of said metal heel members are anchored by molding the material of said composition heel members about and upon both sides of said toe members, central recesses in said composition heel members, and screws having their heads located in the central recesses of said composition heel members, and their shanks passed through the central perforations of said metal heel members and threaded into the sleeves of said metal heel base members.
  - 10 2. In combination with a pair of shoes
  - 15
  - 20
  - 25
  - 30

having heel bases, a pair of metal base members attached to said heel bases substantially flush with the bottoms of said heel bases, and each provided with projections extending into said heel base, and a series of projections extending away from said heel base, and a threaded sleeve recessed into the heel base, a pair of detachable and interchangeable metal heel members having each a central perforation opposite the threaded sleeve of said metal heel base members, and perforations to register with and engage the outward projections of said metal heel base members, a series of radial arms and a series of toe members at the extremities of said radial arms respectively off-set to one side of the plane of the body of said metal heel members, and a pair of molded composition heel members in the body of which the toe members of said metal heel members are anchored by molding the material of said composition heel members about and upon both sides of said toe members, central recesses in said composition heel members, and screws having their heads located in the central recesses of said composition heel members and their shanks passed through the central perforations of said metal heel members and threaded into the sleeves of said metal heel base members.

In testimony whereof I have affixed my signature.

GEORGE A. VOLZ.
